TERMINAL HOUSING FOR LUMINOUS TUBES

Frank Edward Montroy, Los Angeles, Calif.

Application August 30, 1937, Serial No. 161,633

7 Claims. (Cl. 173—328)

This invention relates to a terminal housing for luminous tubes and is directed to the production of a housing which will have a large opening to the interior of the sign body on which it 5 may be installed in order to quickly evacuate dirt, insects and water and provide ample ventilation to evaporate moisture accumulated on the interior surfaces after wet weather. It is also an object to provide a contact spring arrangement which will 10 be secure against turning over and jambing or snapping out of position under pressure of an electrode inserted at an angle, while providing a firm but light contact over a considerable range of movement.

15 Luminous tubes for electric signs are commonly formed by hand in conformity with sheet patterns and are subject to considerable variation. It frequently happens that the center to center distance of the electrodes of a particular tube 20 is too little or too great or that one or both electrodes incline from the perpendicular with the plane of the tube. In such cases trouble is to be expected in making contact with the contact springs in the housings. Similar trouble arises 25 from irregularities in the mounting of the tubes on the sign body and from spring in the body itself due to mechanical flexibility.

It is required of contact springs that they meet the electrode caps over the whole extent of the 30 housing bore and have considerable range of movement while exerting the minimum of pressure against the electrode to avoid straining the glass. These conditions call for springs of relatively light wire with wide convolutions and with the 35 end finished in a flat spiral to provide the contact surface. Such springs very readily turn over and jamb. In housings having continuous bore they often jamb against the electrode and the housing wall. In housings having wide interior openings 40 they often snap out through the opening when the electrode enters at an odd angle and fail to make contact with the electrode cap.

In accordance with my invention the spring is held in position by guiding means which engage 45 each convolution along one side of the spring thereby eliminating all dependence on the housing walls and making possible the openest of constructions. It is an object of this construction to engage each convolution with a three or a four 50 point contact along a limited arc of the turn. The slideway provided by the guide having room for only one wire, it is not possible for the convolutions to pack over each other and jamb. I have found that if a spring is thus retained along one 55 side no other guide is necessary insofar as the

purposes of this service are concerned, and it will compress and expand freely and adjust itself readily to meet the contact caps of electrodes inserted in an irregular manner.

Contrary to common belief the most efficient 5 housings from a standpoint of service under all conditions are not the types which exclude dirt and moisture but the types which most readily rid themselves of such materials. Rain, dirt and insects will accumulate in housings, and it is 10 virtually impossible to keep such matter out unless the housing be sealed at the opening. The use of sealed housings has been found very unsatisfactory from a mechanical standpoint. It 15 also makes for the loss of the air space insulation between the tube wall and the housing wall where the tube passes the grounded metal of the sign body. Present practice inclines almost entirely to the open end housing with preference tending more and more to the selection of types having 20 the larger openings into the interior of the signs. It has been found that the more generous these internal openings be the less trouble is experienced during wet weather. It appears that when 25 wet the open housing develops a certain electrical leakage. This becomes apparent in the flickering of the tubes. With well ventilated housings in which there is little place for dirt to accumulate and form muddy masses the flickering stops 30 soon after wet weather passes and normal service is restored with no permanent damage. Heretofore the necessity of providing a guideway for the contact spring has prevented the use of internal openings sufficient to take the fullest advantage of this principle. It is an object of my 35 invention to take the fullest possible advantage of internal opening into the sign body and to produce housings in which the minimum of opportunity exists for the lodgement of extraneous matter.

It is an object of one species of the invention to provide a housing have a replaceable spring and spring guide assembly to make possible replacements to accommodate different lengths of electrodes. Such housings are useful in connection 45 with shallow sign bodies, and also in connection with special types of electrodes which are longer than common types.

An object of another species of the invention is to provide a spring and spring guide assembly 50 formed integral of a single wire.

I have shown my invention in the accompanying drawings as embodied in several different housing bodies and several different spring constructions. It is to be understood that these 55

forms are largely illustrative and any different combination of body and spring possible from those shown may optionally be used with obvious adaptations. The invention is not limited, however, to the forms shown, nor the combinations which may be thus contrived, but may be variously embodied and adapted to terminal housings within the broadest terms of the appended claims.

The invention is illustrated in its preferred embodiments in the accompanying drawings in which the same numeral appearing in more than one view is to be understood as referring to the same or the equivalent part throughout.

Objects additional to those enumerated above will become apparent in the following description.

Figure 1 is a sectional view through the terminal portion of a luminous tube sign showing a terminal housing made according to my invention in place on a sign body sheeting, connected to a high tension wire and with a tube electrode in position.

Figure 2 is a perspective view of the terminal housing shown in Figure 1.

Figure 3 is a cross section through the spring and guide assembly taken on a plane parallel with the body sheeting of the sign. Figure 4 is a similar cross section of a modification in which the guide is concaved to fit the convolutions of the spring.

Figure 5 is an end view of the spring from the free end showing the manner in which the end of the spring is spiraled to provide a broad contact surface for the electrode cap.

Figure 6 is a side elevation of another type of housing provided with my invention and adapted to be secured to the sign sheeting by a screw flange.

Figure 7 is a sectional view through the upper portion of the housing shown in Figure 6 taken from a vertical plane through the spring guide and the center line of the housing.

Figure 8 is a perspective view of another type of housing showing the spring and spring guide formed integral from a single wire.

Figure 9 is a vertical sectional view of the spring element of the housing shown in Figure 8 taken at a plane through the center line of the housing and facing the spring post.

Figure 10 is a vertical sectional view through the spring element taken at a plane passing through the center line of the housing and the spring post and binding screw.

Figure 11 is a perspective view of the clamp washer used to hold the ends of the spring in position under the binding screw.

In the sectional view in Figure 1 an assembly is shown which is typical of luminous tube sign construction with one of my terminal housings applied. The sign body, indicated by numeral 1, has various luminous tubes positioned in front of the display surface formed by the metal sheeting 2. The end of one of the tubes only is shown. The tube, indicated by 3 terminates in the electrode 4 which enters the housing 6 through the orifice 7. In accordance with common practice the metal cap 8 on the end of the electrode is provided to make contact with the spring 32 in the housing. A high tension cable 10 supported on various insulating posts, one of which is shown and indicated by 11, connects to the binding screw 12 to supply current to the tube. The tube is supported from the sign body by various insulating posts, one of which is shown and indicated by 13.

75 The housing is shown in perspective in Figure

2 and is similar to an open type of simple bushing often used in luminous tube signs. It consists of an annulus 20 provided with flange lugs 21 and 22 for holding the nuts positioned in the depressions 23 and 24. Screws 25 and 26 pass from the outside of the sign sheet through suitable holes into the nuts to hold the device to the sign. A rim 27 extends through the sheet to the outside and provides a certain small surface insulation between the grounded sign body 10 and the tube. The main insulation, however, is secured from the air space. Therefore, the openings in similar commercial housings are made as generous as is consistent with appearances. This embodiment of the invention is directed to simplicity, light weight, low cost and maximum drainage. The length of the annulus is determined by the air space distance required between open metal and ground. The binding screw 12 is positioned just beyond this distance 20 from the sheeting and serves to receive the end of the cable and hold the spring supporting bar 31. The bar is bent over at the end to hold the end of the spring 32. It has a tongued piece 33 pressed from it to form a slide way for the convolutions 30, 30, etc., of the spring. The end 34 of the tongue is bent backward through the opening from which it was pressed to present an inclined surface to the electrode in case the electrode cap should bear against this piece when 30 being inserted into the housing.

As will be seen in Figure 3, the bar thus forms a four point support for each turn of the spring, the outer pieces 35 and 36 being the main stock of the bar after the tongue has been pressed out. 35 In the modification shown in Figure 4 the bar has been concaved to fit the coils more closely. Figure 5 is a view of the contact end of the spring showing the manner in which it is spiraled to provide a broad contacting area to meet the 40 electrode cap.

Housings of the type shown in these views may be adapted to different lengths of electrodes by merely removing the bar and spring assembly and attaching another of a greater or less length.

The housing shown in Figure 6 is of the deep cylinder type provided with a wide side opening. The housing proper consists of the porcelain or glass body 37 which has a flange 38 and rim 39 formed to fit down over the body sheeting on the outside of the sign. Screw threads 40 which project into the sign body accommodate a screw flange or stiff wire clamp member. A hole through the end web 41 accommodates the binding screw 42 which holds the spring 43 and the guide bar 44. In the cross sectional view through these elements shown in Figure 7 it will be seen that the guide bar consists of a rectangular flat metal strip with one end bent at right angles to extend under the screw head and the other end slanted backward to provide a guide for the electrode cap in the event it is inserted in the housing so as to strike the strip. In this device the guideway is formed by the strip and the housing wall with only enough clearance for one wire at a time to pass a given point thus preventing the coil from jambing up on itself.

In the housing shown in Figure 8 the annulus 50 is formed integral with the spring supporting post 51 of dielectric material such as porcelain 70 or glass. It has flange lugs 55 and 56 for securing it to a sign sheeting in the same fashion as the housing shown in Figure 2. The spring assembly 54 is formed integral from a single spring wire and is held by the binding screw 50. One 75

end of the wire is formed in the loop 55 and then through two parallel straight portions 53 and 52 which form the guide, then passing through the loop 56 and into the spring convolutions 51, 51, etc., and terminating in the flat spiral 58. A special clamp washer 61 is formed with a turned down rim 68 which is notched to fit around the wires and hold the two loops firmly together under the head of the binding screw. The end of the guide is slanted back to the post wall at 59 to guide the electrode cap. In this device I eliminate the necessity of forming an extension from the post to the center line of the spring by providing for a firm grip on the first convolution. Repeated tests have shown that springs constructed with any of the types of guides shown herein will operate smoothly, remain true even when the electrode strikes them at sharp angles and are immune from jambing. A properly constructed guide on one side of the spring which prevents the wires from passing each other is entirely adequate for the purpose. While all of my illustrations show four point supports for the convolutions, three point supports will also serve the same purpose.

Housings of the type shown in Figure 2 are preferable for services where simplicity and low cost are important factors. They also are advantageous in that a single stock item may be adapted by a simple change for use with electrodes of different lengths.

Housings of the type shown in Figure 6 are preferred for service in damp climates where surface leakage along the porcelain is an important factor.

Housings of the type shown in Figure 3 combine the advantages of simplicity, low cost and high surface resistance. The positioning of the binding screw on the side makes possible the production of a high quality porcelain piece with minimum cost for the function performed. The side screw also reduces the clearance necessary to the opposite sign body sheeting thus making for more compact signs.

In the claims the term "binding screw" is used in the broad sense of embracing any equivalent fastening means for the spring. The term "housing" is used in the broad sense of trade usage and is to be understood as embracing any type of insulating bushing, ring or casing used to protect the tubes where they pass through the sign body sheeting.

Having thus described my invention, what I claim is:

1. A terminal housing for luminous tubes comprising an annulus adapted to be mounted on a sign body sheeting in registry with an opening therethrough, spring supporting means extending inward with respect to said body from said annulus, a coil compression spring secured at one end to said supporting means with its free end extending backward toward and in alignment with the opening through said annulus and terminating in a closing spiral, and guide means for said spring extending lengthwise therewith and along one side thereof within the major convolutions of said coil to restrain the same against lateral displacement without preventing compression of said coil.

2. A terminal housing for luminous tubes comprising an annulus adapted to be mounted on a sign body sheeting in registry with an opening therethrough, spring supporting means extending inward with respect to said sign body from said annulus and having a surface extending

substantially parallel with the axis of said annulus, a coil compression spring secured at one end to said supporting means and extending backward from said end toward and in alignment with the opening through said annulus and close to said surface with its free end terminating in a closure for said spring adapted to make contact with an electrode inserted in said housing whereby to compress said spring, and guide means for said spring extending substantially parallel to said surface near the same and within the principal convolutions of said coil forming with said surface a guide for said coil to prevent lateral displacement without preventing compression thereof.

3. A terminal housing for luminous tubes comprising an annulus adapted to be mounted on a sign body sheeting in registry with an opening therethrough, spring supporting means extending inward from said annulus with respect to said body, a binding screw near the end of said supporting means, a coil compression spring secured at one end by said binding screw and extending backward from said end toward and in alignment with the opening through said annulus with its free end terminating in a closure for said spring adapted to make contact with an electrode inserted in said housing whereby to compress said spring, and a guide for said coil spring secured at one end by said binding screw and extending lengthwise with said spring, along one side thereof and within the principal convolutions of the coil to restrain the same against lateral displacement without preventing compression thereof.

4. A terminal housing for luminous tubes comprising an annulus adapted to be mounted on a sign body sheeting in registry with an opening therethrough, spring supporting means extending inward from said annulus with respect to said sign body and having a surface extending substantially parallel with the axis of said annulus, a binding screw near the end of said supporting means, a coil compression spring secured at one end by said binding screw and extending backward from said end toward and in alignment with the opening through said annulus and close to said surface with its free end terminating in a closure for said spring adapted to make contact with an electrode inserted in said housing whereby to compress said spring, and a guide for said spring secured at one end by said binding screw extending close to said surface substantially parallel thereto, along one side of said spring and within the principal convolutions thereof.

5. A terminal housing for luminous tubes comprising an annulus adapted to be mounted on a sign body sheeting in alignment with an opening therethrough, spring supporting means integral with said annulus extending inward of said sign body alongside the passageway for electrode terminals and having a surface extending substantially parallel with the axis of said annulus to one side thereof, a binding screw on said spring supporting means near the plane of said surface, and a coil compression spring held at one end by said binding screw and extending backward from said end toward and in alignment with the opening through said annulus with its free end terminating in a closure for said spring adapted to make contact with an electrode inserted in said housing whereby to compress said spring.

6. A terminal housing for luminous tubes com-

prising an annulus adapted to be mounted on a sign body sheeting in alignment with an opening therethrough, spring supporting means integral with said annulus extending inward of said sign body alongside the passageway for electrode terminals and having a surface extending substantially parallel with the axis of said annulus to one side thereof, a binding screw on said spring supporting means near the plane of said surface, a coil compression spring held at one end by said binding screw and extending backward from said end toward and in alignment with the opening through said annulus with its free end terminating in a closure for said spring adapted to make contact with an electrode inserted in said housing whereby to compress said spring, and spring guiding means held by said binding screw extending along and inside said spring to one side thereof near said surface of said supporting means and forming therewith a guide for said spring.

7. A terminal housing for luminous tubes com-

prising an annulus adapted to be mounted on a sign body sheeting in alignment with an opening therethrough, a spring supporting post extending substantially parallel with the axis of said annulus inward of said sign body therefrom, a binding screw on said post, and a unitary wire structure secured to said post by said screw, said wire structure including a convoluted portion forming a coil compression spring extending from said screw back toward the opening through said annulus and in alignment therewith and close to a surface of said post with its free end terminating in a closure for said spring adapted to make contact with an electrode inserted in said housing whereby to compress said spring, and a guide portion extending substantially parallel with said surface of said post close to the same and within the principal convolutions of said spring forming with said post a guide for said spring.
